UNITED STATES PATENT OFFICE

JOHN VAN BRUNT, OF FLUSHING, NEW YORK, ASSIGNOR TO INTERNATIONAL COMBUSTION ENGINEERING CORPORATION, A CORPORATION OF DELAWARE

FURNACE WALL CONSTRUCTION

Application filed July 25, 1925. Serial No. 45,974.

This invention relates to furnace wall constructions and is particularly useful in connection with combustion chambers in which pulverized fuel is burned under stationary boilers, although it is useful in other connections. One of the primary objects of my invention is to provide a simple form of wall construction, whether top bottom or vertical wall.

10 Another object of the invention is to dispense with the more or less complicated and expensive brick wall construction for furnaces of this character and to substitute therefor a very simple form of wall construction, 15 in which expansion and contraction are provided for.

Still another object of the invention is to provide a novel and improved form of water wall construction for furnaces.

20 How the foregoing, together with such other objects as may hereinafter appear, or are incident to my invention are realized, is illustrated in the accompanying drawings, wherein:

25 Fig. 1 is a vertical section thru an upright wall of a combustion chamber embodying my improvements;

Fig. 2 is a fragmentary front elevation of the wall shown in Fig. 1;

30 Fig. 3 is a section taken on the line 3—3 of Fig. 1;

Fig. 4 is a similar cross section drawn on a larger scale to more clearly illustrate the parts, and

35 Fig. 5 is a side elevation of a supporting member.

In the embodiment shown in the drawings the invention is applied to an upright wall, say, for example, the rear wall of the combustion chamber. This wall comprises a base section 7 and a curtain section 8, these two sections being composed of any suitable material, such, for example, as refractory bricks. The section 7 is carried on suitable foundation work and the curtain section 8 is carried on the structural work 9. The gap between these two sections is filled by the wall portion A now to be described.

This wall portion has its inner face, that 50 is the face thereof next the flame, formed of

a plurality of tubes 10. These tubes preferably have longitudinally extending fins 11 arranged in substantial abutment as indicated in Fig. 4 so as to provide, for all practical purposes, a substantially uninterrupted face. 55 The upper and lower ends of the tubes are bent so as to extend outside the wall for connection into the upper and lower headers 12 and 13 respectively, such headers in turn being suitably connected into the circulation 60 of the boiler in any preferred manner. The header 12 is supported from the structural work 9 in the manner illustrated and the header 13 is yieldingly supported by the supporting mechanism indicated as a whole by 65 the reference number 14, whereby the tubes are in effect suspended, expansion and contraction taking place from the header 12, to which end a sand or other yielding joint 15 is provided where the tubes pass thru or over 70 the base section 7 of the wall.

Certain of the tubes 10 are provided on what would be their outer faces with tabs or lugs 16 arranged at suitable intervals lengthwise of the tubes. The tabs are preferably welded to the tubes and secured to the tabs, as by bolts 17, are vertically extending plates 18. Metallic panels 19 extend between the plates 18, the panels being secured together and to such plates by bolts 20 for example. These panels are spaced out from the tubes and the space between the outer faces of the tubes and the panels is filled with a lining 21 composed, for example, of 85 per cent magnesia or similar material. Molded tiles 22, preferably of Sil-o-cel, or the like, fill the gap between the lining 21 and the tubes and fins, these tiles being built up one upon the other. The tiles and lining 20 constitute an insulator to prevent radiation of heat to the exterior as much as possible. They also serve to protect the paneling. A more refractory material is preferable for the tiles as these are nearest the source of 95 hottest temperature, but in this connection it is to be understood that the absorption of heat by the tubes and fins will serve to protect such tile, particularly in view of the fact that the circulation thru the tubes will be 100

very rapid because of their vertical disposition.

It will be apparent from the foregoing that the whole wall A is a suspended one and can expand and contract as a unit. It will also be seen that it is much more simple than the brick walls heretofore employed.

The structural work 9 may be utilized to laterally brace the wall, as by the employment of a horizontally extending angle 23 adapted to bear against the outer face of the wall.

The point where the upper ends of the tubes pass out is preferably packed with yielding material 24 if this is necessary. In any event a friable material is employed in order to permit replacement of tubes.

What I claim is:

1. In a boiler having overhead water tubes heated by convection from the heating gases and having a furnace with a combustion chamber below said tubes, a side wall of said furnace comprising a set of upright water tubes, said wall being supported from above independently of said overhead tubes, and spring means supporting said wall at the bottom thereof and permitting expansion and contraction thereof.

2. In a boiler having overhead water tubes heated by convection from the heating gases and having a furnace with a combustion chamber below said tubes, a side wall of said furnace comprising a set of upright water tubes, said wall being supported from above independently of said overhead tubes, and having the lower ends of the tubes thereof passing through the furnace structure to the exterior thereof, an expansion joint at the point of passage through said structure, and spring means outside the furnace for yieldingly supporting said lower ends of the tubes.

3. In a boiler having overhead water tubes heated by convection from the heating gases and having a furnace with a combustion chamber below said tubes, a side wall of said furnace comprising a set of upright water tubes, said wall being supported from above independently of said overhead tubes, and having the lower ends of the tubes thereof passing through the furnace structure to the exterior thereof, an expansion joint at the point of passage through said structure, a header exterior of the furnace into which the said lower ends of the tubes are connected, and spring means outside the furnace yieldingly supporting said header.

In testimony whereof, I have hereunto signed my name.

JOHN VAN BRUNT.
